UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH.

1,162,864.

Specification of Letters Patent.

Patented Dec. 7, 1915.

Application filed May 22, 1911. Serial No. 628,781.

To all whom it may concern:

Be it known that I, CHARLES J. KLEIN, a citizen of the United States, residing at Milwaukee, in the county of Milwaukee and State of Wisconsin, have invented new and useful Improvements in Electric Switches, of which the following is a full, clear, concise, and exact description, reference being had to the accompanying drawing, forming 10 a part of this specification.

My invention relates to electric switches. In one of its adaptations it more especially relates to switches of the type known as feed through switches; that is, to switches which 15 are arranged to have their terminals connected in one branch of a circuit and have the other branch of the circuit extend through the switch casing.

It has among its objects to provide an 20 improved switch of exceedingly simple, efficient and inexpensive construction.

A further object of my invention is to provide improved means for supporting and inclosing the switch mechanism.

25 Other objects and advantages of my invention will hereinafter appear.

For the purposes of illustration, I shall in this application describe my invention as applied to a switch of the fed through type. 30 My invention itself, however, is not limited in its application to switches of this type, or to the specific construction chosen for purposes of illustration, but may obviously assume other forms and be used in various 35 other relations.

In the accompanying drawings:—Figure 1 shows a central sectional view of an assembled switch. Fig. 2 shows a side elevation of the interior of one of the halves of the 40 switch casing, with the operating member in position in the same. Fig. 3 shows a side elevation of the interior of the other half of the switch casing, with the terminal contacts in position therein. Fig. 4 shows a 45 perspective view of the switch contactor.

In these figures I have illustrated a preferred form of switch mechanism which is of the push button type described in my Patent No. 985,421, patented February 28, 50 1911. This switch mechanism includes a reciprocable cam member 1 of the conformation of a double frustum, positioned base to base, having flanges 2 at its reduced ends and push buttons 3 extending in opposite

directions beyond the flanges 2. A resilient 55 contractor 4 inclosing a garter spring 5, is provided with central perforations 6 through which the cam member passes and is adapted to be thrown upon a movement of the cam member to make or break an electrical circuit with a quick snap action. This contactor is preferably formed of bent resilient sheet metal having a body portion 7, rearwardly extending shoulders 8 and forwardly extending sides 9 bent substantially 65 at right angles to the body portion 7. A transversely extending spacing strip 10, having ears 11 at its corners, is arranged to be fitted into the sides 9 in suitable vertically extending slots 12. In a preferred form 70 the forward edges of the sides 9 are cut off obliquely to form a peaked edge as shown in Fig. 4. In order to provide ample room for the garter spring 5, which is housed between the parts 7 and 10, perforations 13 75 are preferably cut in the sides 9. This switch mechanism is housed in a central position in a casing having two halves 14 and 15, which are preferably composed of a suitable insulating material, and are adapted to 80 be clamped together by screws 16 and 17, respectively above and below the push buttons 3, to form an assembled casing having a substantially oval longitudinal cross section and reduced ends as illustrated in Fig. 85 1. The casing 14, an interior view of which is shown in Fig. 3, is provided with a longitudinally disposed recess 18 of substantially rectangular cross section and carries in this recess the stationary contacts 19 and 20 of 90 the switch. These contacts are arranged near the opposite ends of the casing 14 and are preferably provided with a flat body portion fixed to the casing by suitable screws 21, which extend through to the outside of 95 the base. The screws 16 and 17, which serve to hold the two halves of the casing together, extend through the flat body portion of the contact members 19 and 20. In a preferred form the inner wall of the recess 18 is provided with nipples or sleeves 22 which act as guides for the screws and serve to insulate the same in their passage through the contact members. The inner edges of the contact members 19 and 20 are bent inward 100 substantially at right angles, as at 23, and are received in transversely extending recesses 24, in the bottom of the recess 18.

In a preferred form the edges of the contact members 19 and 20 are slightly rounded along the lines upon which they are bent. The outer ends of the contacts 19 and 20 are provided with ears 25 carrying binding screws 26 adapted to clamp the ends of conductors and are provided with laterally extending ears 27 and upwardly extending lugs 28 to assist in making a good terminal connection. In a preferred form the contacts 19 and 20 are seated in shallow recesses 29, in the bottom of the recess 18, which are of an irregular shape adapted to receive the body portions of the terminal contact and the lugs and ears on the same. Above and below the binding screws 26, the casing 14 is provided with vertically extending rounded grooves 30 which permit the entry of the conductors to the binding screws.

20 In a preferred form slightly deeper transversely extending grooves 31 are formed in the grooves 30 so that insulating washers 32 may be carried in the same. Between the grooves 30, in the opposite ends of the casing 14 and extending along the bottom of the casing on one side, at a depth substantially the same as that of the recess 18, is a groove 33 adapted to receive the conductor which passes through the switch casing. In a preferred form the bottom of this groove is provided with a slightly raised portion 34, which serves to hold the conductor in position in the casing when the casing is assembled.

35 The casing 15 is provided with transversely extending recesses 35 adapted to receive the screws 16 and 17. In a preferred form threaded taps 36 riveted in the casing are provided to receive the ends of these 40 screws and the recesses 35 may communicate with rectangular shaped recesses 37 which fit the taps 36 and are adapted to prevent the rotation of the same. The inner ends of the recesses 35 extend through projections 38 on the inner surface of the casing 15. These 45 projections 38 have enlarged mouths 39 surrounding the inner ends of the recesses 35, which are semi-circular in shape, and preferably communicate with the outer ends of the casing. Horizontally disposed flanges 40 are formed on the inner edges of these extensions 38 and these flanges 40 are arranged to fit over the sleeves or nipples 22 on the casing member 14, as shown in Fig. 1, so that a chamber 41 for the switch mechanism is formed between the two casing members. Due to the provision of the flanges 40 this 55 chamber completely incloses the switch mechanism. Communicating with the chamber 41 on opposite sides are recesses 42 and 43 in the casings 14 and 15, respectively. These recesses 42 and 43 are adapted to receive the ends of the cam member 1 when it is reciprocated within the casing. Communicating with the recesses 42 and 43 are recesses 44 and 45 which extend through the casings 14 and 15 respectively and are adapted to permit the reciprocation of the push buttons 3. The end walls of the recesses 42 and 43 serve as stops for the cam member. The contactor is so positioned on the cam member that its sides 9 are arranged to slide over the bent ends 23 of the terminal contacts 19 and 20 when the cam member is reciprocated to close the circuit of the switch. In order to permit the free movement of the contactor, and to guide the same, transversely extending recesses 46 are provided in the walls constituting the top and bottom of the chamber 41 and in order to limit the backward movement of the contactor and provide a stop against which the flat body portions 7 of the contactor is adapted to abut, transversely extending recesses 47 are provided in the casing 15. By thus recessing the casing 15 a stop 48 is provided between the recesses, which when the contactor is thrown back to open position, shown in Fig. 1, engages the body portion of the contactor and prevents further backward movement of the same, while the rounded portions 8 of the contactor are free to move backward into the recesses 47. Above and below the projections 38 the casing 15 is provided with dished out portions 49 which are opposite the binding screws 26 on the casing 14, and are arranged to receive conductor knots if desired. Above these chambers 49 the ends of the casing 15 are provided with grooves 50 and 51 corresponding to and registering with the grooves 30 and 31 of the opposite casing 14. The two sets of grooves, 30 and 31 and 50 and 51, unite when the casing is assembled to provide suitable passage ways for the conductors and means for holding the insulating washers 32 in position.

When the device is assembled and properly connected in circuit one of the conductors is connected to one of the binding screws 26 while another conductor in the same branch of the circuit is connected to the other binding screw 26. The conductor which constitutes the other branch of the circuit is passed through the switch casing 115 in the groove 33 and clamped between the casing members and engaged by the raised portion 34 in said groove. When the switch is in the position shown in Fig. 1, the circuit of the same is opened and the body portion 120 7 of the contactor rests against the stop 49, the rounded portions of the contactor lying in the grooves 47 and the ears 11 of the contactor lying in the grooves 46. When the cam member 1 is pushed to the left and the crest of the cam passes through the garter spring 5, this garter spring moves rapidly down the right hand slope of the cam to the right or circuit closing position, and the sides of the contactor 9 engage the bent por-

130

tions of the terminal contacts 18 and 19 with a wiping action which tends to reduce the sparking and to keep the contact members clean and bright. The forward limit of 5 travel of the contactor is the stop 52, between the recesses 24, against which the spacing strip 10 of the contactor engages when the latter is in the forward or circuit closing position. Due to the rapid movement 10 of the switch mechanism after the garter spring passes over the crest of the cam, and the improved form of contacts used, the circuit is made or broken very rapidly with little or no arcing at the contacts. Further, 15 due to the provision of the stops limiting the movement of the reciprocable cam member and the stops limiting the movement of the contactor, and the fact that the contactor reaches the limits of its travel substantially 20 the same time that the cam member reaches the limits of its travel, there is little or no strain upon the switch members, so that the switch mechanism is adapted to long service and the shock of impact is exceedingly 25 small. To obtain access to the switch mechanism all that it is necessary to do is to remove the screws 16 and 17 when the two halves of the casing may be separated so that the contact members are accessible. 30

By my improved construction I have been able to provide a switch device which is of a compact and rugged construction and in which the parts are so constructed and arranged as to permit of long use in service. Further, the switch casing is of a convenient form and presents a symmetrical appearance and may be readily connected and disconnected from the conductors when desired. 35 The members of the switch mechanism are securely housed in a closed chamber. Further, the conductor which extends through the switch casing is securely clamped in the same and the arrangement of the casing is such that the weight of the switch mechanism does not rest upon the contact screws. Further, by the provision of the insulated washers in the ends of the casing, the conductors are held securely and snugly in place 45 and are prevented from rubbing and wearing their insulation. Numerous other advantages of my improved construction will be readily apparent to those skilled in the art. 50 While I have in this application described one form which my invention may assume in practice, I have only chosen this form as a means of illustrating the principle of my invention, which itself is capable of assuming many forms and being adapted to various other uses than that herein described. Consequently I do not wish to be limited to the specific construction herein described, but wish to cover all the forms and modifications 55 of which my invention is capable.

What I claim as new and desire to secure by Letters Patent is:—

1. In an electric switch, a switch mechanism of the push button type, a two part casing inclosing the same, terminal contacts 70 for said switch mechanism carried on one of the parts of said casing on opposite sides of said switch mechanism and means for holding the parts of said casing together extending through said contacts. 75

2. In an electric switch, a switch mechanism of the push button type, a two part casing having tapering ends, terminal contacts for said switch mechanism carried in a recess in one of the parts of said casing having a body portion lying flat on the bottom of said recess on opposite sides of said switch mechanism and contact surfaces bent substantially at right angles to said body portions. 80

3. In an electric switch, a snap switch mechanism of the push button type, a two part casing inclosing the same having reduced tapered ends provided with grooves, and a groove in one of the parts of said casing communicating with the grooves in the ends of the same, and terminal contacts for said switch mechanism carried by one of the parts of said casing and arranged on opposite sides of said switch mechanism. 90

4. In an electric switch, a snap switch mechanism of the push button type, a casing inclosing the same having reduced tapered ends provided with grooves and a groove extending through said casing and communicating with the grooves in its ends, terminal contacts carried by one of the parts of said casing having bent contact surfaces located in a plane parallel with the plane of movement of said switch mechanism. 100

5. In an electric switch, a snap switch mechanism of the push button type, a casing inclosing the same, terminal contacts for said switch mechanism insulated from each other and carried in recesses in said casing 110 adjacent its ends, said terminal contacts having bent contact surfaces lying in a plane substantially parallel with the plane of movement of said switch mechanism.

6. In an electric switch, a two part casing of insulating material, a push button operated snap switch mechanism inclosed between the parts thereof, terminal contacts carried by one of the parts of said switch mechanism having their body portions arranged in a plane substantially at right angles to the plane of movement of said switch mechanism and their contact surfaces arranged in a plane substantially parallel to the plane of movement of said switch mechanism, and means for holding the parts of the casing together extending through the body portions of said contact members and insulated therefrom. 120

7. In an electric switch, a snap switch 125

mechanism, a two part casing inclosing the same and having conductor openings in its opposite ends, one of the parts of the casing carrying terminal members for the switch 5 in the opposite ends of a recess in the same adjacent said openings while the other part of said casing is provided with means arranged to inclose the switch mechanism in a closed chamber, both of the parts of said 10 casing being arranged to guide and limit the movement of the operating parts of said switch mechanism.

8. In an electric switch, a snap switch mechanism of the push button type, a two 15 part casing having conductor openings in its opposite ends arranged to guide the operating parts of said switch mechanism and establish the limits of their movement and having suitable recesses arranged to inclose 20 said switch mechanism in a closed chamber, terminal contacts carried by one of the parts of said casing on opposite sides of said switch mechanism adjacent said openings

and means for holding the parts of the casing together.

9. In an electric switch, a push button operated snap switch mechanism, a two part casing inclosing the same, said casing being provided with reduced ends having longitudinally extending grooves and a groove 30 communicating with the grooves in its ends and extending through said casing, terminal members for said switch mechanism carried in one of the parts of said casing having contact surfaces bent away from said switch 35 mechanism and received in grooves in said casing, and means for holding the parts of the casing together passing through said terminal contacts and insulated therefrom.

In witness whereof, I have hereunto subscribed my name in the presence of two 40 witnesses.

CHARLES J. KLEIN.
